CLAIM

The ornamental design for a keyboard instrument for use with a remote synthesizer or the like, as shown and described.

DESCRIPTION

FIG. 1 is a front elevational view of a keyboard instrument for use with a remote synthesizer or the like showing my new design;

FIG. 2 is a top plan view with the strap omitted for convenience of illustration;

FIG. 3 is a right side elevational view thereof;

FIG. 4 is a left side elevational view thereof;

FIG. 5 is a rear elevational view thereof; and

FIG. 6 is a bottom plan view.
